**VACUUM MACHINE PRIMARILY TO BE COUPLED
TO A TUBE TERMINATING ADJACENT A
PARTICLE PRODUCING HANDTOOL**

Anthony Henry James Brockman, London, England,
assignor to Mizers Limited, London, England

Filed July 10, 1972, Ser. No. 270,159

Claims priority, application Great Britain Jan. 10, 1972

Term of patent 14 years

Int. Cl. D15—05

U.S. Cl. D7—166

FIG.1.

FIG.2.

FIG.3.

FIG.4.

FIG. 1 is a front perspective view of the vacuum machine primarily to be coupled to a tube terminating adjacent a particle producing handtool taken from one side thereof;

FIG. 2 is an elevational view of the same vacuum machine primarily to be coupled to a tube terminating adjacent a particle producing handtool taken from the other side thereof;

FIG. 3 is a rear view of the machine of FIGS. 1 and 2; and

FIG. 4 is an underneath plan view of the machine of FIGS. 1 and 2, the top of the article being plain.

I claim:

The ornamental design for a vacuum machine primarily to be coupled to a tube terminating adjacent a particle producing handtool, substantially as shown and described.
